United States Patent Office

Des. 225,961

Patented Jan. 16, 1973

225,961

COMBINATION TOOL

Perry W. Scdoris, 11115 SE. Stark St.,
Portland, Oreg. 97201

Filed Feb. 8, 1971, Ser. No. 113,812

Term of patent 14 years

Int. Cl. D8—05

U.S. Cl. D8—81

Fig. 1

Fig. 2

Fig. 3

Fig. 4

FIG. 1 is a side elevational view of a combination tool showing my new design;

FIG. 2 is a top plan view of the tool;

FIG. 3 is a bottom plan view of the tool; and

FIG. 4 is an enlarged end elevational view taken from the right side of FIG. 1.

I claim:

The ornamental design for a combination tool, as shown.
